HENRY D. JAMES, OF EDGEWOOD PARK, AND RAY E. DE CAMP, OF WILKINSBURG, PENNSYLVANIA, ASSIGNEES TO WESTINGHOUSE ELECTRIC & MANUFACTURING COMPANY, A CORPORATION OF PENNSYLVANIA.

CONTROL SYSTEM.

1,392,060.

Specification of Letters Patent. Patented Sept. 27, 1921.

Application filed May 12, 1919. Serial No. 296,597.

To all whom it may concern:

Be it known that we, HENRY D. JAMES, a citizen of the United States, and a resident of Edgewood Park, in the county of Allegheny and State of Pennsylvania, and RAY E. DE CAMP, a citizen of the United States, and a resident of Wilkinsburg, in the county of Allegheny and State of Pennsylvania, have invented a new and useful Improvement in Control Systems, of which the following is a specification.

Our invention relates to motor-control systems and particularly to systems of the type constituting the subject-matter of a co-pending application by H. D. James, Serial No. 236,937, filed May 27, 1918, and assigned to the Westinghouse Electric & Manufacturing Co., and it has for its object the provision of an improved motor-control system of this character.

Several motor-accelerating systems are illustrated in the above application, in each of which the accelerating resistor is adapted to be short-circuited by contactors under the control of relays which are responsive to the voltage drop of a portion or of the whole of the resistor. The relays may be of the type constituting the subject-matter of a co-pending application by Ray E. De Camp, Serial No. 241,259, filed June 21, 1918, and assigned to the Westinghouse Electric & Manufacturing Co., as shown in Figures 1 and 2 of the above-mentioned James application, or ordinary relays may be employed, as shown in Fig. 6, of the said James application.

According to the present application, relays of either of the above types may be employed but, if the relay of the above-referred to De Camp application be adopted, the main releasing armature, the spring under its control and its associated parts may be dispensed with. The relay coils are normally energized by line voltage to maintain the relays open. A master switch effects initially the closing of the line contactor, whereupon the relay coils become subjected to the voltage drop across the resistor, the relays closing, in accordance with current conditions of the motor, to effect the closing of the resistor-short-circuiting contactors.

Our invention will be made clear in connection with the accompanying description and the drawings, Figs. 1, 2 and 3 of which

are diagrammatic views of control systems embodying our invention.

A motor having an armature 1 and a shunt field-magnet winding 2, is connected between line conductors 3 and 4, separated by a line contactor 5. An accelerating resistor 6 is normally in series with the armature 1. The contactor 5 may be closed by a master switch 7, through the medium of an energizing coil 8, upon the master switch 7 being moved into engagement with a contact member 9. A plurality of contactors 10, 11 and 12 (Figs. 2 and 3) are adapted to be closed to effect the short-circuiting of sections 13, 14 and 15, respectively, of the resistor 6. The contractors 10, 11 and 12 are under the control of energizing coils 19, 20 and 21, which, in Fig. 2, may be energized when the master switch 7 is moved into engagement with a contact member 16 and, in Fig. 3, when the master switch 7 is moved into engagement with contact member 16, 17 and 18, respectively. In the system of Fig. 1, but two contactors 11 and 12 are employed the energizing coils of which are under the control of a single contact member 16. The circuits of the contactor coils are controlled by relays 25, 26 and 27 (Figs. 2 and 3) having a single energizing coil 22 (Fig. 2) or individual energizing coils 22^a, 22^b and 22^c (Figs. 1 and 3) in circuit with a resistor 59 of high resistance which resistor may, if desired, be omitted. The coils 22, 22^a, 22^b and 22^c are normally connected to the line conductors 3 and 4 so as to maintain the relays 25, 26 and 27 in their actuated positions when the motor circuit is open. The relays are shown supplied with springs 30 of different strengths so as to effect the closing of the corresponding relays in accordance with different values of the current traversing the coil 22 or the coils 22^a, 22^b and 22^c. These springs may be replaced by their equivalent mechanisms, as described in the two above-referred-to applications.

The relays may be of the type constituting the subject-matter of the above-mentioned De Camp application, in which event, a single coil 22 may be employed. Any ordinary relays may be employed, however, and a single coil or a plurality of coils may be employed, as desired.

In the system of Figs. 2 and 3, the coil 8 is directly connected across the line conduc-

tors 3 and 4 through the master switch 7 and the contact member 9. In the system of Fig. 1, the circuit of the coil 8 comprises also the relay 25, and a switch 29 is provided, 5 mechanically connected to the contactor 5 so as to establish a holding circuit for the coil 8, following the initial closing of the contactor 5.

The operation will be first described in 10 connection with the system of Fig. 2. The relays 25, 26 and 27 are normally open, as shown. Upon the actuation of the master switch 7 to its first position, in which it engages the contact member 9, a circuit is established 15 from the line conductor 3, through the coil 8, the contact member 9 and the master switch 7, to the line conductor 4. The contactor 5 becomes thereupon closed to establish the motor circuit, which extends from 20 the line conductor 3, through the armature 1 and the resistor 6, and the shunt field-magnet winding 2, in parallel, and the contactor 5, to the line conductor 4. The coil 22 becomes thereupon subjected to the voltage 25 drop of the resistor 6, as it is connected in parallel thereto.

Following the initial acceleration of the motor, the current traversing the motor-circuit will begin to fall in value, subjecting the 30 coil 22 to a decreasing voltage, the value of which is determined by the value of the current traversing the resistor 6. When this voltage falls to a sufficiently low value, the relay 25 is closed by its spring 30 (or by 35 gravity, in case the spring is omitted) whereupon, assuming that the master switch 7 has been actuated to its second position, a circuit will be established from the line conductor 3, through the relay 25, the coil 19, 40 the contact member 16 and the master switch 7, to the line conductor 4. The contactor 10 will thereupon become closed, by its actuating coil 19, to effect the short-circuiting of the resistor section 13. Similarly, upon the 45 subsequent closing of the relays 26 and 27, in accordance with the decreasing value of the voltage drop across the resistor 6, the contactors 11 and 12 will become closed to effect the short-circuiting of the resistor sections 14 and 15.

In Fig. 3, the circuits of the coils 19, 20 and 21 are separately controlled by contact members 16, 17 and 18, thereby providing for controlling the speed of the motor. If 55 the master switch 7 be maintained in its first position, the circuit of the coil 19 cannot become closed, so that the motor will be operated at a first low speed. If the master switch 7 be maintained in its second position, 60 in engagement with the contact members 9 and 16, the circuit of the coil 19 may be closed when the relay 25 becomes closed, but the circuits of the coils 20 and 21 will be maintained open, irrespective of the positions 65 of the relays 26 and 27, thereby provid-

ing for a second speed. In similar fashion, the contactor 12 may be maintained open to provide for a third speed or, if the master switch 7 be actuated to its final position, the operation will be substantially the same 70 as that described above in connection with Fig. 2.

In the system of Fig. 1, two accelerating steps only are provided, but all three relays of the unitary relay structure described in 75 the above-mentioned application by De Camp are employed, one of the relays serving to close the circuit of the coil 8. This circuit extends from the line conductor 3, through the relay 25, (which, unlike the relays 26 and 27, is closed when it occupies its actuated position) the coil 8, the contact member 9 and the master switch 7 to the line conductor 4. Upon the closing of the contactor 5 by its energizing coil 8, the motor 80 circuit is closed and the coils 22^a, 22^b, and 22^c are energized by the voltage drop of the resistor 6. The opening of the relay 25, upon the voltage of the resistor 6 falling to a predetermined value, effects the opening 85 of the above-traced circuit of the coil 8. A holding circuit for this coil is, however, previously established from the line conductor 3, through the switch 29, the coil 8, the contact member 9 and the master switch 7, 90 to the line conductor 4. The operation of the relays 26 and 27 to effect the closing of the contactors 11 and 12 is substantially the same as that of the corresponding parts of the systems of Figs. 2 and 3.

According to our present invention, therefore, the relays that control the resistor-short-circuiting contactors are maintained open by line voltage to insure the resistor 95 6 being in circuit with the armature 1 at the time that the motor circuit is closed by the contactor 5. Upon the closing of the motor circuit, however, the control of the relays is transferred to the resistor 6, their subsequent operation being substantially the same as 10 that described in the aforementioned application by James. The necessity for the maintaining spring and the releasing armature of the above-referred-to De Camp relay is thus eliminated.

Obvious and desirable modifications will occur to those skilled in the art. We desire, therefore, that the appended claims shall be construed broadly, except in so far as limitations may be specifically imposed therein. 11

We claim as our invention:

1. The combination with an electric motor having an armature, a resistor in series therewith, a switch for short-circuiting said resistor, a relay for said switch that is biased 1 to closed position and having an opening coil, and a source of energy for said motor, of means whereby the voltage of said source is applied to said coil when said motor is disconnected from said source and whereby 1

- 1 said coil is energized in accordance with the drop in potential across said resistor when said motor is connected to said source.
2. The combination with an electric motor having an armature, a resistor in series therewith, a switch for short-circuiting said resistor, a relay for said switch that is biased to closed position and having an opening coil, a source of energy for said motor, and
- 5 a switch for connecting said motor to said source, of a second relay that is biased to open position and having a closing coil, means normally connecting said coils to said source, and means for closing said connecting switch and thereby connecting the first-named coil across said resistor.
3. The combination with an electric motor, a resistor associated therewith and a source of energy, means controlled successively in accordance with the voltage of said source and the voltage drop of said resistor for controlling said resistor, and a switch for closing the circuit of said motor, of a master switch having two positions, in the
- 20 first of which it effects the closing of said circuit-closing switch and in the second of which it controls said controlling means.
4. The combination with an electric motor having an armature, a resistor in series therewith, a switch for short-circuiting said resistor and having an actuating coil, a relay for said switch having an actuating coil in parallel circuit with said resistor, and a switch for closing the circuit of said motor,
- 25 of a master switch having two positions, in the first of which it effects the closing of said circuit-closing switch and in the second of which it partly closes the circuit of said switch coil.
- 40 5. The combination with an electric motor having an armature, a resistor in series therewith, a switch for short-circuiting said resistor and having an actuating coil, and a switch for closing the circuit of said motor and having an actuating coil, of a pair of relays controlled in accordance with the drop in potential across said resistor for respectively controlling the circuits of said coils, means for closing first the circuit of said
- 45 50 circuit-closing-switch coil through one of said relays and then the circuit of said resistor - short - circuiting - switch coil through said other relay, and means for maintaining said circuit-closing-switch coil energized.
- 55 6. The combination with an electric motor having an armature, a resistor in series therewith, a plurality of switches for short-circuiting said resistor, each having an ac-

tuating coil, a relay for each of said switches and having an actuating coil connected across said resistor, and a line switch for closing the circuit of said motor having an actuating coil, of a master switch for controlling the circuit of the actuating coil of line closing-switch in one of its positions and for partly closing the circuits of said resistor-short-circuiting switch coils in its other position.

7. The combination with an electric motor having an armature, a resistor in series therewith, a source of energy for said motor, a plurality of switches for short-circuiting said resistor, each having an actuating coil, and a switch for closing the circuit of said motor and having an actuating coil, of a relay for each of said switches and having an actuating coil connected initially to said source and later across said resistor, and a master switch having a plurality of positions in each of which it controls the circuit of one of said switch coils.

8. The combination with a source of energy, an electric motor, a resistor in circuit therewith and means for controlling said resistor, of means successively controlled in accordance with the voltage of said source and with the drop in potential across said resistor for controlling said resistor-controlling means.

9. The combination with a source of energy, an electric motor, a resistor in circuit therewith and means comprising a plurality of switches for controlling said resistor, of means comprising a plurality of relays that are successively controlled in accordance with the voltage of said source and with the drop in potential across said resistor for controlling said switches, and means for initiating the operation of said motor.

10. The combination with a source of energy, an electric motor, a resistor in circuit therewith and means for controlling said resistor, of means successively controlled in accordance with the voltage of said source and with the drop in potential across said resistor for controlling said resistor-controlling means, and means for initiating the operation of said motor and for effecting the successive control of said resistor-controlling means.

In testimony whereof, we have hereunto subscribed our names this 29th day of April, 1919.

HENRY D. JAMES.
RAY E. DE CAMP.
